UNITED STATES PATENT OFFICE.

ALBERT F. FROUSSARD, OF ST. LOUIS, MISSOURI.

SHOE MACHINE.

Application filed February 27, 1919. Serial No. 279,496.

To all whom it may concern:

Be it known that I, ALBERT F. FROUSSARD, a citizen of the United States of America, residing at the city of St. Louis, State of Missouri, United States of America, have invented a certain new and useful Shoe Machine, of which the following is such a full, clear, and exact description as will enable any one skilled in the art to which it appertains to make and use the same, reference being had to the accompanying drawings, forming part of this specification.

My invention relates to a shoe machine and more particularly to a machine for enclosing the toe, for pressing the inturned flange of the upper, and for forming the box toe of a shoe.

In the accompanying drawings which illustrate one form of machine made in accordance with my invention, Fig. 1 is a side elevation of the complete machine, Fig. 2 is a front elevation, a portion of the last support being broken away, Fig. 3 is an enlarged detail view of the jaw slide, the cover plate being removed, Fig. 4 is a view similar to Fig. 3 but showing the parts in different position, Fig. 5 is a front view of the box toe forming mold, Fig. 6 is a top plan view of the parts shown in Fig. 2, Fig. 7 is a vertical longitudinal section of the upper part of the machine, Fig. 8 is a section taken on the line 8—8 of Fig. 7 and Fig. 9 is a section taken on the line 9—9 of Fig. 7.

10 indicates the base of the machine which base carries a pedestal 11 to which is pivoted at 12 a table support 13. Secured to the table support 13 is a guide 14 provided with a way 15 in which travels the flattened upper 40 end of a threaded rod 16 passing through a correspondingly threaded gear wheel 17 carried on a bracket 18. The gear wheel 17 meshes with the second gear 19 operated by a crank arm 20 to raise and lower the rod 16 and thus tilt the table support 13 on its pivot 12. Slidingly mounted in the table support 13 is a table 21. The table 21 is provided with a rack 22 (Fig. 7) engaging with a pinion 23 for sliding the table in 50 the table support. The pinion 23 is operated by a hand wheel 24. Pivotally mounted on the table 21 by means of a stud 25 is a block 26 provided with a segmental rack 27 engaging with a worm wheel 28 operated 55 by a hand wheel 29. Mounted in the block 26 is a sleeve 30 carrying on its forward

end the jaw slide 31. Arranged in the jaw slide 31 are a pair of jaws 32, each of which is provided with a cam slot 33 engaging with a pin 34 in the opposite jaw. 60 Each of the jaws is also provided with a second cam slot 35 having a forward extension 36. These slots 35 engage with a pin 37 carried in the jaw slide 31. Jaws 32 are engaged by links 38 pivoted to a cross bar 39 carried on a rod 40 extending through the sleeve 30, and provided at its rear end with a cam cylinder 41 loosely mounted between a collar 42 and disc 43. The cam cylinder 41 is provided with a cam 70 slot 44, as best shown in Fig. 6, which engages with a pin 45 carried in an arm 46 attached to the block 26. The cylinder 41 is operated by means of a handle 47. Attached to the jaws 32 are blades 48 as shown 75 in Figs. 3 and 4 or box toe molds 49 as shown in Fig. 5. These blades and molds are interchangeable by means of bolts 50. In order to rotate the sleeve 30, the said sleeve is provided with a collar 51 carrying 80 a segmental rack 52 engaging with a worm 53 operated by a hand wheel 54.

Slidingly mounted on the base 10 is a standard 58 in which is slidingly mounted the stem 59 of the last support. This stem 85 59 is connected by means of yokes 60 and 61 with a treadle 62 for vertically reciprocating said stem. In order to adjust the height to which the last is raised, a rod 63 provided with right and left hand threads, is 90 preferably interposed between the yokes 60 and 61. In order to move the standard 58 toward and away from the table 21, the said standard is attached to a threaded rod 64 connected with a hand wheel 65. The upper 95 end of the stem 59 has pivotally secured to it at 70 a last supporting member 71 provided with a pin 72 adapted to slide in a suitable opening in the heel of the last 73. This last supporting member 71 is adapted 100 to be operated on the pivot 70 by means of a cam 74 engaging with a curved arm 75 carried on the said member 71. The upper end of the stem 59 has also secured to it a vertically movable block 76 to which is pivoted at 77 an arm 78 carrying on its upper end an adjustable toe support 79 adapted to engage with the toe of the last 73.

The operation of the machine is as follows: The last is removed from the support 71 and the shoe placed thereon after which the shoe and last together are placed

in position in the machine. The toe of the shoe is held firmly against the support 79 by operating the cam 74. The last may be adjusted to any suitable angle by means of the pivoted arm 78. The jaws are adjusted to the shoe by means of the crank 20 and the hand wheels 29 and 54. The last may be adjusted towards and away from the jaws by means of the hand wheel 65 or the jaws 10 may be adjusted to the last by means of the hand wheel 24. After the proper adjustments are made if it is desired to enclose the toe, the last is first raised by depressing the treadle 62 and the operating rod 40 15 forced forward by means of the cam 41. The first movement of the rod 40 will cause the jaws 32 to move bodily forward, thus bringing the blades 48 against the toe of the shoe. As soon as the pin 37 has moved 20 out of the extension 36 of the slots 35, the forward movement of the jaws will be arrested and the jaws forced to move pivotally together by the combined action of the cam slots 33 and 35 thus enclosing the toe. In 25 order to press the inturned flange of the upper, the jaws are first closed and the last 73 carrying the shoe then forced upwardly by means of the treadle 62. In order to form a box toe, the blades 48 are replaced 30 by the box toe mold 49, the operation being the same as when enclosing the toe.

Having fully described my invention, what I claim as new and desire to secure by Letters Patent of the United States is:

35 1. In a shoe machine, the combination with a support, of a member mounted thereon and capable of both pivotal and sliding movement, clamping jaws, a longitudinal movable shaft for actuating said jaws, and 40 a manually operated cam drum mounted on said shaft to move the same longitudinally.

2. In a shoe machine, the combination with a support, of a member mounted thereon and capable of both pivotal and sliding movement, clamping jaws, means for adjusting said jaws around an axis lying substantially in their working plane, a longitudinally movable shaft for actuating said jaws, and a manually operated cam drum mounted on said shaft to move the jaws 50 longitudinally. 45

3. In a shoe machine, the combination with a support, of a member mounted thereon and capable of both pivotal and sliding movement, a sleeve rotatably mounted in 55 said member, clamping jaws, a longitudinally movable shaft passing through said sleeve, and means for rotating said shaft to operate said jaws.

4. In a shoe machine, the combination 60 with a support, of a member mounted thereon and capable of both pivotal and sliding movement, a sleeve rotatably mounted in said member, clamping jaws, a longitudinally movable shaft passing through said 65 sleeve, and a manually operated cam drum carried by said shaft for actuating said jaws.

5. In a shoe machine, the combination with a base, of a support pivotally 70 mounted on said base and provided with a guide way, a threaded rod carrying said base and having a flattened end engaging with the guide way in said support, an internally threaded gear engaging with said 75 rod to move the same longitudinally to turn said support on its pivot, a table mounted on the support, and clamping jaws slidingly carried on said table.

In testimony whereof, I have hereunto set 80 my hand and affixed my seal.

ALBERT F. FROUSSARD. [L. S.]
